UNITED STATES PATENT OFFICE.

JOHN A. KNIGHT, OF AUBURN, MAINE.

VINEGAR-MEASURE.

SPECIFICATION forming part of Letters Patent No. 288,946, dated November 20, 1883.

Application filed March 15, 1882. Renewed August 22, 1883. (No model.)

To all whom it may concern:

Be it known that I, JOHN A. KNIGHT, of Auburn, in the county of Androscoggin and State of Maine, have invented certain new and useful Improvements in Vinegar-Measures; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 is a plan of the sheet forming the walls of the measure. Fig. 2 is a sectional view of the bottom. Fig. 3 is a view of the handle. Fig. 4 is a side view of Fig. 1 fastened together at its ends.

Same letters show like parts.

My invention relates to vinegar-measures. It is well known that when these vessels are made of certain kinds of metal they corrode and in time become useless.

I am aware that measuring-vessels for this purpose have before this been made of wood, as mine is, but not of the peculiar construction which mine exhibits. Measuring-vessels for vinegar have been constructed of staves, like ordinary water-pails, with the larger end for the bottom, and then hooped with metal. I do not claim such implements.

I first take what is known as "scale-board" in the green state and stamp it out into sheets of flaring form, such as seen at Fig. 1 in the drawings. By "scale-board" I mean thin sheets or veneers of wood cut off from the periphery of logs by proper machinery for the purpose.

Before this has become dry I form it as illustrated in the drawings at Fig. 1, and then a short distance from the lower end of the widest part, 40 at *a*, I make a groove or channel, *b*. The bottom is made with a thin edge or periphery, (see *d*, Fig. 2,) and so as to fit into this groove. The sheet of scale-board is then wrapped around the bottom piece, with the edge of the 45 bottom piece entering the groove. The edges of the scale-board overlap. The lap is then fastened down by any familiar means, as by rivets, &c. Hoops made of wire are then placed around the vessel, as seen in Fig. 3. 50 Either the top or bottom hoop is, after passing around the cup or vessel, brought together and bent up so as to form a handle. (See *e*.) The end of this bent part or handle is then attached to one of the other hoops, as seen in Fig. 3. 55 Any convenient material may be used for the hoops, if of metal, tough, and flexible.

What I claim as my invention, and desire to secure by Letters Patent, is—

The vinegar-measure herein described, composed of the scale-board body-piece cut into form and grooved, as described, and bent around the wood bottom, the wood bottom, the rivets, and the hoops, one of which is formed of the same piece of metal as the handle, and is united with the other hoop, as herein set forth.

In testimony that I claim the foregoing as my own I affix my signature in presence of two witnesses.

JOHN A. KNIGHT.

Witnesses:

WILLIAM HENRY CLIFFORD,
JOHN P. KERRIGAN.
